UNITED STATES PATENT OFFICE.

MARY E. RADICK, OF WHITE PLAINS, NEW YORK

DOLL'S HEAD.

1,138,412.

Specification of Letters Patent.

Patented May 4, 1915.

Application filed January 20, 1915. Serial No. 3,247.

To all whom it may concern:

Be it known that I, MARY E. RADICK, a citizen of the United States, and a resident of White Plains, in the county of West-
5 chester and State of New York, have invented a new and Improved Doll's Head, of which the following is a full, clear, and exact description.

My invention relates to doll heads adapt-
10 ed to give more than one facial expression to the doll.

An object of the invention is to provide a doll head having a plurality of faces, each having a different expression with means
15 whereby any one of the faces may be ex- posed while the others are covered so that the child can give different facial expressions to its doll, as for example, the doll's head may have one face expressing happy-
20 ness and the other sorrow, etc.

With the above and other objects in view, the nature of which will more fully appear as the description proceeds, the invention consists in the above construction, combina-
25 tion and arrangement of parts as herein fully described, illustrated and claimed.

In the accompanying drawings forming part of the application similar characters of reference indicate corresponding parts in all
30 the views, and Figure 1 is a perspective view of my doll head embodying the invention; Fig. 2 is a perspective view as seen without the wig, and looking on to the other faces of the doll's head; Fig. 3 is a vertical sec-
35 tion through the doll's head showing the smiling face exposed while the unsmiling face is covered by the wig; Fig. 4 is a similar section to Fig. 3 but showing the sorrowing face exposed, the smiling face being covered
40 by the wig.

Referring to the drawings 5 represents a doll's head having two diametrically opposite faces 6 and 7, one face having an expression different from the other, and which expressions can be varied to suit individual tastes. A wig 8 is pivotally connected to the doll's head at the apex of the head by means of a pin 9 having a head 10 and a split end 11, the head of the pin retaining the wig
45 against the head, while the pin forms the axis on which the wig is mounted to swing or turn. The pin 9 is retained in position by opening up the split ends 11 of the pin

against the washer 12 bearing against the inner surface of the doll's head adjacent the apex; thus a free turning movement of the wig is obtained. The wig 8 is large enough to entirely cover the other face or faces, and only expose one of the faces as shown in Fig. 1. It is self evident that any other suitable means for pivotally attaching the wig 8 may be provided, and that any style of wig can be used in connection with the doll's head provided the wig covers substantially the other face or faces. A child desiring to ex-
55 pose a face normally covered by the wig 8 simply takes hold of the wig and shifts the same to uncover the face originally cov-
60 ered. This movement of the wig will automatically cover the other face which was originally exposed, leaving the originally cov-
65 ered face exposed. It is self evident that any combination of facial expressions can be obtained to suit the individual taste of a child, which in combination with the swing-
70 ing wig will permit the child to expose any one of the faces while the others are un-
75 exposed.

From the foregoing description taken in connection with the accompanying drawings, the advantage of the construction and operation of the device shown will be readily understood by those skilled in the art to which the invention pertains; and while I have described the principle of operation
80 together with the features which I now consider to be the best embodiment thereof, I desire to have it understood that the device shown is merely illustrative, and that such changes may be made as are within the scope of the appended claims.

What I claim is—

1. A doll head having two faces diamet-
rically opposite, the expression of said faces being different, a wig pivotally connected to
95 the apex of the doll's head whereby the same can be moved on the head and thereby ex-
pose one of the faces while the other is cov-
ered by the wig.

2. A doll head having two faces diamet-
rically opposite, a pin at the apex of the doll's head, a wig associated with the pin and turnable thereon, said wig adapted to cover any one of the faces while exposing
100 the other substantially as and for the pur-
pose set forth.

3. A doll head having a plurality of faces, a wig mounted to swing on the apex of the head, said wig adapted to expose any one of the faces while covering the other faces substantially as and for the purpose set forth.

In testimony whereof I have signed my

name to this specification in the presence of two subscribing witnesses.

MARY E. RADICK.
